UNITED STATES PATENT OFFICE.

JESSE CONVER AND CHARLES B. KOONS, OF PHILADELPHIA, PA.

IMPROVEMENT IN WASTE-WATER PIPES.

Specification forming part of Letters Patent No. 127,850, dated June 11, 1872.

Specification describing an Improved Waste-Water Pipe, invented by JESSE CONVER and CHARLES B. KOONS, both of Philadelphia, Pennsylvania.

Our invention consists of a water-pipe having the fold or folds described hereafter, so that the interior of the pipe may be of the cylindrical shape best adapted to the free flow of water. A longitudinal flange, facilitating the attachment of the pipe, is provided, while the pipe is at liberty to expand and accommodate itself to the ice which accumulates during severe winter months.

Figure 1 is a front view of our improved waste-water pipe, and Fig. 2 a transverse section of the same.

The sheet metal of which the pipe A is composed is folded at two points, *a a*, the fold forming external ribs, without, however, interrupting, to any material extent, the cylindrical interior of the pipe, for the two sides of each fold are in contact with each other at *x*.

It is well known that water flows more freely through a cylindrical pipe than through a pipe of any other form; hence the preservation of the interior of our improved pipe in a cylindrical or nearly-cylindrical shape, as shown.

While our improved pipe possesses all the advantages of an ordinary cylindrical pipe as

regards the free flow of water through the same, it is at liberty, owing to the presence of the folds, to expand and accommodate itself to the ice which accumulates inside the pipe during the severe winter months, and which tends to disrupt ordinary pipes. It will also be seen that the longitudinal flanges afford a ready means of securing the pipes to the fronts of buildings, staples on which may be arranged to embrace or clutch the flanges.

Although we prefer that the pipe should have two folds, *a*, arranged as shown, it might, in some instances, be constructed with one fold, and in other cases with more than two. Without, therefore, confining ourselves to the number of folds,

We claim—

A cylindrical pipe provided with a fold or folds, *a*, forming longitudinal flanges on the outside of the pipe, as and for the purpose described.

In testimony whereof we have signed our names to this specification in the presence of two subscribing witnesses.

JESSE CONVER.
CHAS. B. KOONS.
